H. E. REESE,

UNITED STATES PATENT OFFICE.

HARRY E. REESE, OF GYPSUM, KANSAS.

MOTOR-CYCLE SUPPORT.

1,209,029.

Specification of Letters Patent. Patented Dec. 19, 1916.

Application filed October 13, 1915. Serial No. 55,709.

To all whom it may concern:

Be it known that I, HARRY E. REESE, a citizen of the United States, residing at Gypsum, in the county of Saline and State of Kansas, have invented new and useful Improvements in Motor-Cycle Supports, of which the following is a specification.

This invention relates to certain novel and useful improvements in supporting devices 10 for motorcycles and analogous vehicles and has particular application to a telescopic support.

I am aware of the fact that it has hitherto been proposed to provide telescopic supports for bicycles, such supports embracing a stationary outer section having one end secured to the frame of the vehicle, and a 15 slidable inner section telescopically arranged within the outer section and movable into and out of such outer section by way of the remaining end thereof, the inner section being held within the outer section by means 20 of a spring and in outer or extended position by means of a catch carried by the outer section; but, so far as I am aware, 25 these devices are more or less cumbersome in structure and the parts are so arranged and correlated as to be inaccessible.

In carrying out my invention, I propose 30 to provide a device of the class described wherein the inner and outer sections and the spring for holding such inner section in the outer section will be so arranged relatively to one another that access may be quickly 35 and conveniently had to the device whenever it is desired to repair or replace mutilated or broken parts.

My invention consists in the construction, combination and arrangement of parts hereinafter set forth in and falling within the scope of the claim.

In the accompanying drawing; Figure 1 is a fragmentary side elevation of a motorcycle equipped with a support constructed 45 in accordance with the present invention. Fig. 2 is a vertical central sectional view through the support. Fig. 3 is a transverse sectional view therethrough.

Referring now to the drawing in detail, 50 1 designates an outer sleeve-like section having the opposite ends thereof open and 2 indicates an inner sleeve-like section slidably mounted within the outer section 1. Formed on the outer surface of the inner section 2 55 and extending longitudinally thereof are rack teeth 3, while pivoted upon the outer

section 1 adjacent to the lower end thereof is a dog 4 working through an opening 5 in the outer section and coöperating with the teeth 3 and adapted to hold the inner 60 section 2 in distended position.

Arranged transversely of the outer section 1 adjacent to the upper end thereof is a rod 6 having the ends thereof secured to the outer section at diametrically opposite points, while arranged across the inner section 2 in proximity to the lower extremity thereof is a cross rod 7 having the ends thereof secured to the inner section at diametrically opposite points. 70

8 designates a coiled retractile spring having one end secured to the cross rod 6 and the remaining extremity fastened to the cross rod 7. This spring acts to hold the inner section 2 in its innermost position 75 within the outer section 1 and when the inner section is pulled out of the outer section, the dog 4 is engaged in an adjacent tooth 3 to hold the inner section against movement into the outer section under the 80 action of the spring 8.

Fastened to the lower end of the inner section is a foot plate 9, while secured to the upper end of the outer section 1 is a cap 10 carrying a clamp 11 of some suitable 85 construction. The lower end of the inner section 2 carrying the foot 9 is bent laterally toward the wheel of the motorcycle so that the foot may engage the ground immediately adjacent to the tread of the wheel, 90 thereby forming a substantial bearing for the support.

In practice, the clamp 11 is fastened to one of the bars of the frame of the motorcycle and as long as the motorcycle is in motion the inner section is held in its innermost position within the outer section by means of the spring 8. When, however, it is desired to support the motorcycle, the inner section is pulled downwardly under 100 the action of the foot plate 9 against the action of the spring 8 when the plate is in engagement with the ground, the foot may be withdrawn from the plate and the dog 4 will engage an adjacent tooth 3 to hold 105 the sections 1 and 2 in proper relative positions so as to support the motorcycle.

The sections 1 and 2 of the support are preferably oval shaped in cross-section, as clearly illustrated in Fig. 3 of the drawings, 110 so as to prevent relative turning movement of the sections.

While I have herein shown and described one preferred form of my invention by way of illustration, I wish it to be understood that I do not limit or confine myself to the precise details of construction herein described and delineated, as modification and variation may be made within the scope of the claim and without departing from the spirit of the invention.

10 I claim:

A telescopic support for motorcycles and the like comprising an outer sleeve-like section and an inner sleeve-like section capable of sliding movement within the first-mentioned section, said first-mentioned section being formed with an opening adjacent to the lower end thereof, a spring actuated dog pivoted upon the first-named section and working in said opening, said inner

section being formed with teeth adapted to 20 register with the opening in the outer section to receive said dog in the outward movement of said inner section to hold the sections adjusted, cross rods carried by the outer ends of said sections, a retractile 25 spring arranged within said sections and having the ends thereof connected to said cross rods respectively whereby the inner section may be drawn into the outer section upon the release of said inner section by said dog, and a foot plate on the lower end of said inner section.

30 In testimony whereof I affix my signature in presence of two witnesses.

HARRY E. REESE.
